UNITED STATES PATENT OFFICE.

CREIGHTON F. BALDWIN, OF ST. LOUIS, MISSOURI.

COUNTING MACHINE.

1,409,646.

Specification of Letters Patent. Patented Mar. 14, 1922.

Application filed October 31, 1919. Serial No. 334,737.

To all whom it may concern:

Be it known that I, CREIGHTON F. BALDWIN, a citizen of the United States, residing in the city of St. Louis and State of Missouri, have invented new and useful Improvements in Counting Machines, of which the following is a specification, reference being had to the accompanying drawings.

The present invention pertains to counting machines, and the chief purpose of the invention is to provide a counting machine especially adapted for counting furs, although it may be adapted to other uses.

In the large establishments where furs are handled, it is the practice to assort them into various grades. Then the furs of each grade are counted separately. This counting is usually done mentally, the numbers being carried in mind by the operator.

Thus mistakes are very apt to occur.

The primary object of the present invention, therefore, is to provide a machine which will automatically register the number of furs passed through it.

A secondary object is to provide such a machine with a swinging gate under which the furs are successively passed; the oscillations of the gate in turn being automatically registered upon a suitable counter.

A further object is to produce the machine in a simple, practical and efficient form best adapted for the purposes intended.

In the drawings:

Figure 1 is a top plan view.

Figure 2, a side elevation.

Figure 3, an end elevation.

Figures 4, 5 and 6 are details of the cam and sliding shaft mechanisms which operate the counter.

Fig. 7 is a detail showing in perspective the arrangement of the counter actuating lever and attached elements.

Referring more particularly to the drawings, in carrying out my invention in its preferred construction, I provide a primary table 1, mounted upon the legs 2, and a secondary, adjustable table 3, which is pivoted by means of brackets 5 to the bearing rod 4 extended between the legs of the primary table 1. The secondary table 3 is also provided with outwardly positioned folding legs 6, hinged beneath the secondary table 3 by means of hinges 7 so that the legs 6 may be readily folded up underneath the secondary table 3 and thus permit the secondary table to assume an inclined position, with its outer

end resting upon the ground. Toggle levers 8 afford means for bracing the legs 6 in upright position when the secondary table 3 is elevated. It will be noted that the secondary table stands lower than the primary table. This arrangement is to accommodate furs which are passed from the primary table onto the secondary table and so that a pile of furs may accumulate on the secondary table without rising above the surface of the primary table and obstructing the operator. As these piles accumulate they are carried away by boys. However, should a boy be delayed in his work in carrying away the piles of furs, the operator may lower the outer end of the secondary table by folding up the legs 6, as indicated, and thus the furs will slide to the ground and a considerable number may be permitted to accumulate without interfering with or delaying the operator. This is the purpose of the adjustable feature of the secondary table.

Transversely across the end of the primary table 1, adjacent the secondary table 2, is rigidly mounted a swinging gate 9, same being pivotally suspended from a rod 10, the rod 10 being mounted upon an upright 11, the latter in turn being rigidly mounted upon the table 1. The gate 9 is pivotally suspended from the rod 10 by means of rings 12 secured to the upper edge of the gate 9, encircling the rod 10. The rod 10 is mounted freely through the rings 12 so as to permit the gate 9 to swing easily back and forth. The inner ring has a portion of its periphery cut away so as to leave a cutout 13 which has a square shoulder 14. Adjacent this cutout is mounted a cam 15 upon its pivot 16. This cam is triangular shaped, with one leg 17 extended into the cutout 13 and so that the shoulder 14 will impinge thereupon as the gate 9 swings back and forth. The other leg 18 of the cam 15 extends forwardly and clear of the cutout 13. A sliding shaft 19 is mounted longitudinally along the rod 10, being held freely in place by means of the guide 20. The inner end of this sliding shaft is provided with a roller 21 which is nicely adjusted into contact with the leg 18 of the cam 15. The outer end of the sliding shaft 19 is pivoted by means of the pivot 22 to the lower end of a bell crank lever 23, the latter being pivoted through its angle by means of a pivot 24 to the bracket 25. The outer end of the bell crank lever 23 is bent forwardly upon itself at

right angles so as to form an outstanding end 26. From the outer extremity of this end 26 is pivoted the rod 27—28 by means of a pivot 29. The two sections 27 and 28 are 5 connected by a turn buckle 30 by means of which the sections 27 and 28 may be extended or drawn together for the purposes of adjustment. The lower end of the section 28 is pivoted to the arm 31 of the counter 32 10 by means of a pivot 33. The counter 32 is rigidly mounted upon the bar 10. A spring 35 attached and stretched between the point 40 on the shaft 19 and the point 41 on the rod 10 serves normally to throw the shaft 15 19 inwardly, with the roller 21 constantly in contact with the cam leg 18. The inner end of the rod 10 may be squared, and thus slidingly passed through the square mortise 36, by which arrangement the gate 9 may be 20 readily adjusted to various widths of tables.

In operation as the furs are counted from the table 1 they are passed through the gate 9, the gate 9 being swung outwardly for this purpose, and as the gate 9 operates 25 back and forth, the shoulder 14, formed in the ring 12, comes into contact with the leg 17 of the cam 15, which causes the leg 18 of said cam to move outwardly and force the sliding shaft 19 outwardly along the rod 30 20, thus swinging the upper arm of the bell crank lever 23 and the lever 27—28 upwardly, causing the counter to register one unit for each oscillation of the gate 9, and

thus the count of the furs passed through the gate 9 is automatically taken care of and 35 registered upon the counter 32.

While I have herein described a certain specific method of constructing and assembling the elements of my invention, it is understood same may be varied in minor details, not departing from the spirit of my invention as defined in the appended claim. 40

What I claim to be new and patentable is:

A counting mechanism, comprising a supporting table; a rod mounted horizontally 45 across one end of the table and spaced upwardly therefrom; a gate pivoted to said rod from its upper edge by means of rings; a counter mounted adjacent said gate; and a lever system connecting the gate with the counter, said system embodying a shouldered recess formed in one of the supporting rings of the gate; a triangular cam mounted on the rod with one leg adapted to play into said recess; a sliding shaft mounted longitudinally along the rod, with its inner end in contact with the other leg of said triangular cam; a bell crank lever pivoted from one arm to the outer end of the sliding shaft, and having its other arm operatively connected with said counter. 50 55 60
